W. O. PRICE,

RAIL JOINT.

APPLICATION FILED NOV. 6, 1916.

Patented July 31, 1917.

UNITED STATES PATENT OFFICE.

WILLIAM O. PRICE, OF SELMA, LOUISIANA.

RAIL-JOINT.

1,234,801.

Specification of Letters Patent.

Patented July 31, 1917.

Application filed November 6, 1916. Serial No. 129,819.

To all whom it may concern:

Be it known that I, WILLIAM O. PRICE, a citizen of the United States of America, residing at Selma, in the parish of Grant 5 and State of Louisiana, have invented certain new and useful Improvements in Rail-Joints, of which the following is a specification, reference being had therein to the accompanying drawing.

10 This invention relates to rail joints and has for its principal object the production of a joint which is constructed so as to interlock when in an assembled condition, thereby eliminating any possibility of the 15 warping or springing of the abutting ends of two rails when in use.

Another object of this invention is the production of a rail joint wherein the interlocking construction caused by the mitered 20 ends of the treads of two rails will prevent the ends from chipping off due to the passing of the wheels of a train thereover, owing to the fact that as the wheels pass over the 25 joint they will at all times be resting upon one end of either rail.

A still further object of this invention is the production of a rail joint wherein the interlocking construction will cause the ends to fit snugly upon each other and thus resist 30 side movement or springing action of the rails independent of the fish plate, thereby reducing the strain of the fish plate and causing the ends of the rails to remain in engagement with each other under all conditions.

With these and other objects in view this invention consists of certain novel combinations, constructions, and arrangements of parts as will be hereinafter fully described 40 and claimed.

In the accompanying drawing:

Figure 1 is a top plan view of the rail joint as constructed in accordance with this invention.

45 Fig. 2 is a side elevation of the rail joint with one fish plate removed.

Fig. 3 is a central horizontal section taken on the line 3—3 of Fig. 2 of the complete device.

50 Fig. 4 is a vertical section taken on the line 4—4 of Fig. 2.

Fig. 5 is a detail perspective view of one end of one rail.

55 Fig. 6 is a detail perspective view of the structure as shown in Fig. 5 and illustrating the opposite side thereof.

Referring to the accompanying drawing by numerals it will be seen that the rail joint comprises a pair of rails which have similarly constructed ends so as to cause the 60 ends to positively interlock when the rails are assembled for positively holding the rails in alinement with each other. Therefore, it is thought that a description of one rail will be sufficient to comprehensively 65 disclose the construction of both the rails as herein disclosed, and, accordingly, 1 designates the web of the rail, which is formed upon the usual broad base 2, while the tread 3 of the usual construction is formed integral upon the web 1. The web 1 is reduced longitudinally, as indicated at 4 and has a portion of the base 2 extending from the side thereof, as shown at 2'. The numeral 2 represents the entire base, while 2' 70 indicates only a fragment thereof. The web 1 has a slanting shoulder 5 which extends at an angle of approximately 45° to a horizontal plane, as shown in Figs. 2 and 5. The tread 3, however, terminates at a distance 75 beyond the slanting shoulder 5 although the reduced projecting portion 4 of the web extends for a considerable distance beyond the end of the tread 3, as shown clearly in Figs. 5 and 6. The end of the tread 3 is 80 cut so as to extend diagonally across the central longitudinal axis of the tread 3, thus presenting a slanting abutment 6. The reduced portion 4 slants rearwardly toward its upper portion, as shown in Figs. 5 and 85 6, slanting in the opposite direction to the shoulder 5 of the web 1.

Since, as above stated, the sections of the joint are similarly constructed it is obvious that when the two abutting ends of the rails 90 are positioned in engagement with each other the various slanting or diagonal portions thereof will extend in opposite directions for permitting the same to register with each other and thus form interlocking 95 or mitered joints.

When the two sections of the rail are positioned so as to have the abutting ends interlocking it will be seen that the two reduced portions 4 of the web of the rail will 100 fit upon each other, and under the treads of the abutting ends of the rails. The diagonally extending abutments of the ends of the treads will fit adjacent each other although, of course, it is necessary to leave sufficient 105 space as shown in Fig. 1, to provide for the expansion and contraction of the rails, due

to atmospheric conditions. The slanting ends 7 of the reduced portions of the webs of the rails as well as the ends of the fragments of the base shown at 2' abut against 5 the slanting shoulders 5 of the webs of the two rails. When this assembling of the two ends of the two rails has taken place it is obvious that the openings 8 extending through the webs 1 of the reduced portions 10 4 thereof will register with each other so as to permit the fish plates 9 having openings 10 formed therein to be positioned so as to permit the openings 10 to register with the openings 8. Bolts 11 may be passed through 15 the openings 10 and 8 so as to cause the projecting ends of the bolts 11 to carry the nuts 12 and thus positively hold the fish plates upon the side portions of the webs 1. In this manner it will be seen that the two 20 abutting ends of the rails will be positively held against accidental disengagement when in use. It is obvious, however, that by having the projecting portions 4 of the webs 1 fitting under the treads of the rails and their 25 slanting ends engaging the slanting shoulders 5 of the webs any tendency toward upward springing action on the part of the abutting ends of the rails will be positively prevented. It is further obvious that be- 30 cause of the mitered fitting diagonal abutments 6 of the treads 3 upon each other and the overlapping webs any side movement of the abutting ends of the rails is prevented and, therefore, the rails will be positively 35 held in alinement with each other independently of the fish plates, bolts and nuts. Furthermore, it will be seen that as the abutments 6 extend diagonally across the longitudinal axis of the abutting ends of the rails 40 the usual jarring which takes place as a wheel passes over the abutting ends of two rails is eliminated, since a wheel passing over the joint will be resting upon one or the other ends of the two rails at all times. 45 Accordingly, not only jarring is eliminated but the ends are also prevented from chipping or breaking off as is the case when the abutting ends of two rails are positioned adjacent each other, and sufficient space is 50 allowed for the expansion and contraction of the rails due to atmospheric conditions.

From the foregoing description it will be seen that a very simple and efficient rail joint has been provided wherein the fitting of the diagonal abutments of the treads 55 against each other and the slanting ends of the webs upon the slanting shoulders of the webs will positively hold the rails in alinement with each other and in such a manner as to permit a train to pass over the joint 60 without causing any noticeable jarring action, and, furthermore, it will be seen that the interlocking construction of the rail joint will hold the same from springing or warping from its correct position whereby 65 the ordinary rail trouble which so frequently causes disastrous wrecks is prevented.

What is claimed is:—

A rail joint of the class described, comprising a pair of similarly constructed sections, each section comprising a base having a web formed thereon, a tread carried upon said web, said web being reduced longitudinally adjacent its ends, said reduced portion having a base extending from one side thereof, the end of said reduced portion slanting rearwardly toward its top portion, said tread terminating short of the end of said reduced portion of said web, the end of said tread extending diagonally across 70 the longitudinal axis of said section, said web being provided with a slanting shoulder extending at an angle of substantially 45° with respect to a horizontal plane, said shoulder extending upwardly under said tread, whereby when the two sections are positioned in engagement with each other the reduced portions of the webs will bear upon each other so as to cause the slanting ends thereof to engage the slanting shoulders of said webs while the diagonal abutments of said treads will fit adjacent each other, whereby the diagonal abutments and the slanting ends and shoulders will hold said sections against side movement or upward movement or any other warping action, and said diagonal abutments being adapted to present an even riding surface 80 when the two sections engage each other.

In testimony whereof I hereunto affix my 85 signature.

WILLIAM O. PRICE.
